UNITED STATES PATENT OFFICE.

LESLIE R. McDONALD, OF MONTREAL, QUEBEC, CANADA.

DISPLAY APPARATUS.

Application filed November 14, 1924. Serial No. 749,857.

My invention relates to that class of display apparatuses wherein a considerable number of disconnected placards are exhibited one by one, successively removed from view position, reversed, and the reversed side exhibited; and my improvements are directed to the details of construction of such an apparatus.

An object of my improvements is to maintain the foremost placard at a suitable angle for exhibition, until the next placard appears, when it may be allowed to fall back against the pack.

Another object of my invention is to improve the means for receiving a placard when it is lowered toward view position and to gradually bring it down under the influence of the placard withdrawing mechanism.

Another object of my invention is to introduce improved means for preventing the premature reappearance of any placard before its proper time.

And still another object of my invention is to so construct the apparatus that placards may be readily inserted or removed without disassembling the apparatus.

In the drawings Fig. 1 is a front elevation of my improved apparatus with the casing partly removed; Fig. 2 is a side elevation taken on the line 2—2 of Fig. 1, with the side of the casing removed; Fig. 3 is a vertical sectional view taken on the line 3—3 of Fig. 1, looking to the right; Fig. 4 is a view of the upper part of the apparatus taken on the same line as Fig. 3, but showing the upper part of the mechanism tilted back to allow access to the placard reservoir; Fig. 5 is a plan view of the placard pack carrying and shifting mechanism; and Fig. 6 is a cross sectional view of the same taken on the line 6—6 of Fig. 5. Figs. 5 and 6 are on an enlarged scale.

In all the figures similar parts are designated by corresponding reference numerals.

As usual in apparatuses of this general character, the mechanism is preferably arranged within a case 1, provided with an open or glazed front 2 behind which the placards 3, 3 are to be successively exhibited.

These placards may be conveniently supported on a pair of worms 4, 5 journaled in the framework of the apparatus having respectively threads of opposite pitches, terminating rearwardly in grooved cams 6, 7 and driven by suitable gearing as worm

gears 8, 9, meshing with worms 10, 11 on a shaft 12 driven by a worm gear 14 meshing with a worm 15 from the shaft 16 of an electric motor 17.

The placards 3, 3 are provided with dovetailed notches 18 in their top and bottom edges, adapted to cooperate with a detent 19 mounted in the base of the machine, preferably provided with a depressed and laterally tapered forward end 20 and slidably held in a support 21, to which it is detachably attached as by a spring 22, the free end of which may be sprung into and out of a socket in the edge of the detent. This arrangement permits the detent to be slid backward off its base so as to permit the removal and substitution of placards as desired. The depression and lateral tapering of the forward end of the detent adapt it to enter the notches in the cards with certainty even if a card is slightly displaced when it approaches the detent. As the placards are carried back along the detent it will hold them all down with the exception of the rearmost placard, which will pass back off the detent before it is raised by eccentrics on the worms so as to be grasped between the belts 25, 25 and the roller 26, and carried forward between the belts and the rollers 27, 28, 29, 30, 31 and 32, and allowed to drop down into view position in the front of the apparatus.

The belts 25, 25 also travel over suitable carrying rollers 35, 36, 37 and 38, suitably mounted in the frame of the apparatus and driven by the motor 17 through a sprocket 40 on shaft 12, sprocket chain 41 and sprocket 42 on shaft 43 of the roller 35; another sprocket 44 on shaft 43 driving a sprocket chain 45 travelling also around the sprocket 46 on shaft 47 of roller 38.

As the placard is dropped down to the front of the apparatus it is directed by suitable edge guides 50, 50, so that its lower edge will fall upon the sloping receptor 51 down which it may slide until it rests upon the cross head 52, provided with a rearwardly disposed flange 53 and carried by the bar 54, pivoted, as at 55, in the base of the apparatus and extended so that its inner end 56 rocks up against the cam 6. The relative adjustment of the parts is such that when a placard is dropped down in front of the apparatus it will encounter the cross head 52 in an elevated position, as shown in Fig. 3, the rotation of the cam

6 allowing the cross head to drop down, allowing the placard to rest upon the un-grooved portions 58 and 59 of the forward ends of the worms 4 and 5, the turning of 5 the worms bringing the ends of their grooves beneath the edge of the placard and starting the placard on its backward travel.

This arrangement avoids bruising the bottom of the placards when they are lowered into position, as might, possibly, occur if they fell directly upon the curved surfaces of the worms.

A shaft 62 is journalled in the framework of the apparatus, and through a 15 sprocket 63 is driven by the sprocket chain 45.

A worm 64 on shaft 62 drives a worm gear 65 on a shaft 66 mounted in a bearing 67 carried by a transversely disposed rod 68, 20 the forward end of the shaft 66 being provided with a worm 69 having a comparatively broad thread preferably extending over two full turns. When a placard is dropped into view position its top will lean 25 back against the face of the worm; and as the worm revolves its free end will pass in front of the upper edge of the placard, which will gradually be moved back as the worm revolves, so that when the bottom of 30 the placard has been turned back by the worms 4 and 5, so as to make room for the next placard to be exhibited, the top of the retiring placard will have been withdrawn by the worm 69, so as not to interfere with 35 the succeeding placard. After the tops of the placards pass the worm 69 they fall naturally against the pack behind them.

To assist in raising the rearmost placard it 40 is of advantage to use a positively driven roller 72, preferably of rubber or similar material, which is shown as mounted on a shaft 73 carrying a sprocket 74, driven by the sprocket chain 41. This assists the 45 top of the placard in overcoming the friction of the weight of the pack leaning against it.

In the practical use of such an apparatus it is important to provide for ready access 50 to the placard reservoir for the purpose of changing the placards. This I do by assembling the system of the placard shifting rollers, including the apparatus for supporting the top of the forward placard, as a unit between suitable head plates 76 and 77; the shaft 43 passing through suitable bearings 55 at the tops of the end frames 78, 79, so that the roller unit may be rocked up, as illustrated in Fig. 4 and adjusted or moved into a different position relative to the rest of the apparatus, thus affording ready access 60 through the top of the apparatus.

By means of my improvements I obtain a compact and comparatively simple apparatus for the efficient exhibition of independent placards, which are successively released from down-holding means, raised,

shifted, and reversed; dropped toward and then gently lowered into view position; supported at a suitable angle while being exhibited, and as gradually retired, are allowed to fall back upon the placard pack; and which operates by the down-holding means being readily releasable to allow changing of the placards, and the placard receiving spaces being reached with facility by swinging back the top element of the mechanism.

I wish it to be understood that the apparatus illustrated is to be considered as a typical illustration of the embodiment of my improvements and not as an exclusive form. For it is obvious that details of construction might be modified as by substitution of mechanical equivalents, without departing from the spirit of my invention as claimed.

Having thus described my invention, what I claim and desire to secure by Letters Patent of the United States, is:—

1. In a display apparatus, the combination of a plurality of independent, flexible placards with supporting and shifting means, means for raising, transferring from rear to front, and lowering the placards successively edgewise onto the supporting means in relatively spaced positions, and means for temporarily preventing the top of each placard from falling back under the influence of gravity, against those behind it while being exhibited.

2. In a display apparatus, the combination of a plurality of independent, flexible placards with supporting and shifting means, means for raising, transferring from rear to front, and lowering the placards successively edgewise onto the supporting means in relatively spaced positions, and moving means for temporarily preventing the top of each placard from falling back under the influence of gravity, against those behind it while being exhibited.

3. In a display apparatus, the combination of a plurality of independent, flexible placards with supporting and shifting means, means for raising, transferring from rear to front, and lowering the placards successively edgewise onto the supporting means in relatively spaced positions, and means embodying a worm for temporarily preventing the top of each placard from falling back under the influence of gravity, against those behind it while being exhibited.

4. In a display apparatus, the combination of a plurality of independent, flexible placards with supporting and shifting means, means for raising, transferring from rear to front, and lowering the placards successively edgewise onto the supporting means in relatively spaced positions, and means embodying a worm having a comparatively

wide thread for temporarily preventing the top of each placard from falling back under the influence of gravity, against those behind it while being exhibited.

5. In a display apparatus, the combination of a plurality of independent, flexible placards with supporting and shifting means, means for raising, transferring from rear to front, and lowering the placards successively edgewise onto the supporting means in relatively spaced positions, and means for temporarily preventing the top of each placard from falling back under the influence of gravity, against those behind it while being exhibited and for permitting it to fall back against the placard pack when a new placard has been lowered into view position.

6. In a display apparatus, the combination of a plurality of independent, flexible placards with supporting and shifting means, means for raising, transferring from rear to front, and lowering the placards successively, and movable means for preliminarily receiving each placard when lowered and then gradually lowering it to the shifting means.

7. In a display apparatus, the combination of a plurality of independent, flexible placards with supporting and shifting means, means for raising, transferring from rear to front, and lowering the placards successively, and means adapted to be raised to preliminarily receive each placard when lowered and then depressed to gradually lower it to the shifting means.

8. In a display apparatus, the combination of a plurality of independent, flexible placards with supporting and shifting means, means for raising, transferring from rear to front, and lowering the placards successively, and means adapted to be raised to preliminarily receive each placard midway of its width and to be depressed to lower the placard to the shifting means.

9. In a display apparatus, the combination of a plurality of independent, flexible placards with supporting and shifting means, means for raising, transferring from rear to front, and lowering the placards successively, and means actuated by the shifting means and adapted to be raised to preliminarily receive each placard when lowered and then gradually lower it to the shifting means.

55. 10. In a display apparatus, the combination of a plurality of independent, flexible placards with supporting and shifting means, means for raising, transferring from rear to front, and lowering the placards successively, and means embodying a rocking bar having a cross head adapted to be raised to preliminarily receive each placard when lowered and then gradually depressed to lower it to the shifting means.

60. 11. In a display apparatus, the combina-

tion of a plurality of independent, flexible placards with supporting means and means for shifting and preliminarily raising each placard successively, supplementary raising means engaging with the back of the placard, and transferring and reversing means.

12. In a display apparatus, the combination of a plurality of independent, flexible placards with supporting means and means for shifting and preliminarily raising each placard successively, supplementary raising means embodying a driven roller engaging with the back of the placard, and transferring and reversing means.

13. In a display apparatus, the combination of a plurality of independent, flexible placards with supporting means and means for shifting and preliminarily raising each placard successively, supplementary raising means embodying a driven roller provided with a surface adapted to cling to the placard, and transferring and reversing means.

14. In a display apparatus, the combination of a plurality of independent, flexible placards with supporting means and means for shifting and preliminarily raising each placard successively, supplementary raising means embodying a roller having a smooth rubber face engaging with the back of the placard, and transferring and reversing means.

15. In a display apparatus, the combination of a plurality of independent, flexible placards with supporting and shifting means, readily detachable placard detaining means, adapted to engage with the lower portions of the placards, means for initiating the separation of the placards successively, and placard transferring and reversing means.

16. In a display apparatus, the combination of a plurality of independent, flexible placards with supporting and shifting means, placard detaining means embodying a sliding element detachably connected with a support and adapted to engage with the lower portions of the placards.

17. In a display apparatus, the combination of a plurality of independent, flexible placards with supporting and shifting means, said placards having dovetail notches therein, placard detaining means, embodying a sliding element having a forwardly depressed and tapered end, detachably connected with a support and adapted to engage with the lower portions of the placards by entering said dovetail notches therein.

18. In a display apparatus for exhibiting in succession a plurality of flexible placards, the combination of a common frame work, placard supporting and rearwardly shifting means arranged in a unitary assembly within the framework, and placard raising, transferring and reversing means arranged

in another unitary assembly pivotally mounted within the framework and readily adjustable as a whole into different positions relative to the first mentioned unitary assembly.

19. In a display apparatus for exhibiting in succession a plurality of flexible placards, the combination of a common framework, placard supporting and rearwardly shifting means arranged in a unitary assembly within the framework, and placard raising, transferring, reversing and placard top supporting means arranged in another unitary assembly pivotally mounted within the framework and readily adjustable as a whole into different positions relative to the first mentioned unitary assembly.

20. In a display apparatus for exhibiting in succession a plurality of flexible placards, the combination of a common framework, common actuating means, placard supporting and rearwardly shifting means arranged in a unitary assembly within the framework, and placard raising, transferring and reversing means arranged in another unitary assembly pivotally mounted within the framework and readily adjustable as a whole into different positions relative to the first mentioned unitary assembly without disturbance of the normal relations of the two assemblies to the common actuating means.

21. In a display apparatus for exhibiting in succession a plurality of flexible placards, the combination of a common framework, placard supporting and rearwardly shifting means arranged in a unitary assembly within the framework below a placard reservoir, and placard raising, transferring and reversing means arranged in another unitary assembly mounted within the framework above the placard reservoir and readily adjustable as a whole into different positions relative to the first mentioned unitary assembly to afford ready access to the placard reservoir.

22. In a display apparatus for exhibiting

in succession a plurality of flexible placards, the combination of a common framework, common actuating means, placard supporting and rearwardly shifting means arranged in a unitary assembly within the framework below a placard reservoir, and placard raising, transferring and reversing means arranged in another unitary assembly mounted within the framework above the placard reservoir and readily adjustable as a whole into different positions relative to the first mentioned unitary assembly to afford ready access to the placard reservoir without disturbance of the normal relations of the two assemblies to the common actuating means.

23. In a display apparatus, the combination of a plurality of independent, flexible placards with supporting, shifting and initially raising means, readily detachable placard detaining means, supplementary raising means engaging with the back of each placard successively, means for drawing up, transferring and reversing the placards successively, means for temporarily supporting the top of each placard when in view position, and means for preliminarily receiving each placard and lowering it to the shifting means.

24. In a display apparatus, the combination of a plurality of independent, flexible placards with supporting, shifting and initially raising means, readily detachable placard detaining means, supplementary raising means engaging with the back of each placard successively, means for drawing up, transferring and reversing the placards successively, means for temporarily supporting the top of each placard when in view position, and means for preliminarily receiving each placard and lowering it to the shifting means, the means for drawing up, transferring and reversing and supporting the tops of the placards being in a unitary assembly readily separable from the rest of the apparatus.

LESLIE R. McDONALD.
